UNITED STATES PATENT OFFICE.

FREDERICK N. GARDNER, OF BELOIT, WISCONSIN.

GRINDING OR POLISHING MACHINE.

No. 920,859.

Specification of Letters Patent.

Patented May 4, 1909.

Application filed April 24, 1907. Serial No. 369,932.

To all whom it may concern:

Be it known that I, FREDERICK N. GARDNER, a citizen of the United States, residing at Beloit, in the county of Rock and State of Wisconsin, have invented certain new and useful Improvements in Grinding or Polishing Machines, of which the following is a specification.

The object of this invention is the production of an improved grinding or polishing machine.

The invention contemplates a machine comprising a plurality of grinding elements, and means for carrying an article successively into operative relation with said grinding elements.

The invention also relates to a machine comprising a grinding element, and means for carrying an article into operative relation with said element, the latter being arranged at an angle with relation to the line of movement of the article.

The invention further refers to a machine comprising two opposing grinding elements, and means for carrying an article through the space between said elements, said elements being disposed at an angle with relation to each other and to the line of travel of the article.

The embodiment herein illustrated of my invention is intended for grinding the polygonal sides of nuts, cap-screw heads or similar articles, and comprises a plurality of pairs of opposing grinding disks arranged to grind two opposite sides or faces of the article, the number of pairs of grinding disks employed depending upon the number of faces to be ground.

The machine also comprises means for carrying the articles to be operated upon successively between the disks of each pair of grinding disks, and means between each two successive pairs of disks for placing the articles in position to be acted upon by the next succeeding pair.

In the accompanying drawings, Figure 1 is a side elevation, with parts broken away, of a grinding machine embodying the features of my invention. Fig. 2 is an end elevation thereof. Fig. 3 is a partial top plan of the machine. Fig. 4 is a detail view of the article-positioning device. Figs. 5 and 6 are detail views of the article-holders.

In the embodiment selected for illustration, the mechanism is supported upon a base 1, upon the opposite sides of which are se-

cured three pairs of brackets 2. Each of these brackets comprises a guide-way 3 having overhanging side walls. In said guide-way is slidably mounted a block 4 having bearings 5 therein for rotatably supporting a shaft 6. Upon the inner end of said shaft is rigidly mounted a grinding disk 7, of any common or preferred construction, and between the bearings 5 said shaft carries a drive pulley 8 arranged to be driven from a countershaft (not shown) supported above the machine. By reference to the drawings, it will be seen that the construction set forth provides a plurality of pairs of opposing grinding disks. To permit of adjusting the disks of each pair toward and away from each other I mount a screw 9 in bearings 10 and 11 located at opposite ends of the guide-way 3, said screw being provided at its outer end with a crank 12 for turning it. Upon the screw 9 is a nut 13 having a stem 14 extending through a bearing 15 in the block 4. The upper end of the stem is screw-threaded to receive a nut 16. As will be seen, the rotation of the screw 9 moves the grinding disk carried upon the block 4 attached to said screw toward or away from the opposite disk.

The articles to be operated upon are moved through the space between the grinding disks of each pair, said disks being disposed at an angle with each other and with the direction of travel of the articles to provide a V-shape space (Fig. 3) between them. In their travel through said space, from the broad forward end to the narrow end thereof, two opposite faces of the articles are ground off to the desired extent. The depth of the cut to be made by the grinding disks is regulated by adjusting the inclination of said disks, the blocks 4 for this purpose being pivotally mounted to swing in a horizontal plane upon the stems 14. Any suitable means may be provided for adjusting the angle of inclination of the disks 7 and for locking them in the desired position. In the present instance, the means employed for this purpose comprises two lugs 17 preferably fixed to or cast integral with the brackets 1 at one side of the guide way 3, said lugs having oppositely inclined or wedging faces. Upon opposite ends of the block 4, in position to bear against said lugs, are mounted screws 18 having conical inner ends adapted to engage the inclined faces of said lugs. As will be apparent, the angle at

which the grinding disks 7 is placed with relation to the line of travel of the article to be operated upon may be adjusted by slackening one of the screws 18 and screwing up the other, said screws also serving to lock the block 4 against pivotal movement.

The means herein shown for feeding the articles through the machine comprises an endless conveyer 19 consisting of holders 20 pivotally joined together by means of links 21 to form an endless series of holders. The particular form of the holder is, of course, varied to suit the article to be conveyed. Where the machine is to operate upon nuts, each holder comprises a stud 22 upon which the nuts are pivotally mounted. Where it is desired to operate upon cap screws, holders having an opening 23 therethrough to receive the body of the screw are used, the head of the screw resting upon the upper side of the holder.

The endless conveyer 19 is carried upon a driving sprocket wheel 24 fixed upon a shaft 25 which is rotatably supported in bearings 26 at one end of the base 1, and upon a wheel 27 mounted upon a shaft 28 running in bearings 29 at the opposite end of said base. The shaft 25 carries at one end a worm wheel 30 with which meshes a worm 31 fixed upon the upper end of a vertical shaft 32 rotatably supported in bearings 33. On the lower end of the shaft 32 is fixed a bevel gear wheel 34 meshing with a similar gear 35 fixed upon a shaft 36 rotatably mounted in a bearing 37 upon the base 1. The shaft 36 also carries a stepped pulley 38 arranged to receive a belt (not shown) extending over a similar pulley 39 fixed upon a shaft 40 carried in a bracket 41 fixed to one side of the base 1. The shaft 40 also carries a drive pulley 42 adapted to receive power from any suitable source.

The upper part of the endless conveyer 19 is supported to travel horizontally in a straight line by means comprising, in this instance, a rail 43 formed for convenience in sections, said sections being bolted to standards 44 rising from the base 1. The lower half of said endless conveyer runs through a channel 45 provided in the base 1.

The articles to be operated upon are placed upon the conveyer 19 by an operator standing at the left-hand end of the machine, Fig. 1. After the article has been passed between the first two grinding disks and two of its opposite faces have been ground, the article is turned into position to present two other opposite faces to the next succeeding pair of grinding disks by means to be now described.

Between adjacent pairs of grinding disks are mounted casings 46, said casings each having at its opposite ends studs 47 slidably mounted in elongated openings 48 formed in certain of the standards 44. Nuts 49 turned

upon the screw-threaded outer ends of said studs secure the casing 46 in adjusted position. The casing has a guide-way 50 therein through which the upper parts of the holders 20 travel. At the point 51 the guide-way 50 is enlarged to permit the article passing through said guide-way to be turned. In this instance, the means for turning the article consists of a plunger 52 slidably mounted in an opening 53 formed in the casing 46, the operative end of said plunger extending into the path of movement of the article passing through the guide-way. The plunger 52 has a stem 54 which is slidably mounted in a screw plug 55 closing one end of the opening 53. Between the plunger 52 and said screw is included a coiled spring 56 yielding holding the plunger 52 into position to engage the articles passing through the guide-way 50.

In operation, power is supplied to rotate the grinding disks 7 and for operating the conveyer 19. The grinding disks of each pair of disks are adjusted in position toward or away from each other according to the size of the article to be operated upon, and said disks are placed at an angle with the line of movement of the articles suitable to produce the depth of cut desired. The first pair of disks operates upon two opposite sides or faces of the article, the plunger 52 between the first and second pairs of disks turns the article into position for two other of its opposite sides to be acted upon by the second pair of disks, and so on for the remainder of the series of operations. It will be seen that each disk constitutes means for holding the article against the opposite disk. After passing the last pair of disks the articles drop from the holders 20 into a suitable receptacle (not shown).

The machine herein shown may be used in various ways and for a number of purposes. For example, each pair of operating members 7 may be of different character or quality from the others. The first pair may be grinding disks adapted to make a rough cut and the succeeding grinding disks to make successively finer cuts, the positioning devices 46 52 being removed or held from action.

It is evident that the details of the several parts and mechanisms of the machine and their relative order or arrangement may be varied in many respects without departing from the principle of the invention.

I claim as my invention:

1. In a grinding machine, in combination, a grinding device; an endless conveyer for carrying an article into contact with and past said device; and means for holding the article against said device, said device being arranged at an angle with the path of the article, the portion of the grinding device which extends in the direction from which

the article approaches being farther from the path of the article than the opposite portion of said device, whereby the article is gradually ground to the size determined by the 5 position of the portion of the device last contacted by the article.

2. In a grinding or polishing machine, in combination, two opposite grinding or polishing elements disposed at an angle with 10 relation to each other; means for actuating said elements; and a conveyer for carrying an article through the space between said elements from the wider to the narrower part of said space.

15 3. In a grinding or polishing machine, in combination, a supporting member having a guide-way therein; a block slidably mounted in said guide-way and adapted for partial rotation therein; a screw; bearings on said 20 supporting member for said screw; a nut on said screw, said nut having a stem forming a pivot for said block; and a bearing in said block for said stem.

4. In a grinding or polishing machine, in 25 combination, a base; brackets secured in pairs to opposite sides of said base; means on each of said brackets for rotatably supporting a grinding element; means on each of said brackets for longitudinally moving 30 and rotating said supporting means; a conveyer wheel mounted at each end of said

base; means for rotating one of said conveyer wheels; a conveyer belt extending over said wheels and through the spaces between the pairs of grinding elements; and a 35 rail for supporting said conveyer belt between said conveyer wheels.

5. In a grinding or polishing machine, in combination, a member having a guideway therein; a block slidably mounted in said guideway and provided with bearings; a shaft rotatably mounted in said bearings; a grinding element fixed to said shaft; means for rotating said shaft; an adjusting screw rotatably mounted in said member; a nut on said screw; a stem on said nut serving as a pivot for said block; and means for pivotally moving said block.

6. In a grinding or polishing machine, in combination, two pairs of opposing grinding elements; means for carrying an article through the spaces between said elements and from one pair to the other; and means for turning said article between said pairs of elements comprising a member having a 55 guideway therein and a yieldingly mounted plunger extending into said guideway and adapted to engage the article.

FREDERICK N. GARDNER.
